UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,010, dated December 7, 1897.

Application filed October 23, 1897. Serial No. 656,235. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a description.

My invention relates to designs for prism-plates.

Figure 1 is a plan view of a prism-plate embodying my design. Fig. 2 is a cross-section therethrough with parts broken away and enlarged.

A is the body of a prism-plate; B B, a series of surface areas on one side thereof formed by the lines of separation C C.

D D are a series of prisms on one side of the plate, and E E are prisms on certain of the surface areas grouped so as to form a sort of

ring or hollow square intermediate between 20 the center and an outer edge of the prism-plate.

The essential features of my invention are found in the prism-plate, comprising a substantially flat extended body with a series of 25 lines of separation on one side to divide the surface into a series of substantially uniform surface areas, a series of prisms on the other side, and prisms on certain of the surface areas arranged in a sort of hollow square intermediate between the center and edge. 30

I claim—

A design for a prism-plate, substantially as shown and described.

FRANK L. WRIGHT.
